(57) **CLAIM**

The ornamental design for an electronic cigarette case, as shown and described.

DESCRIPTION

FIG. 1 is a front elevational view of an electronic cigarette case;

FIG. 2 is a rear elevational view of the electronic cigarette case;

FIG. 3 is a top plan view of the electronic cigarette case;

FIG. 4 is a bottom plan view of the electronic cigarette case;

FIG. 5 is a left side elevational view of the electronic cigarette case;

FIG. 6 is a right side elevational view of the electronic cigarette case;

FIG. 7 is a first perspective view of the electronic cigarette case;

FIG. 8 is a second perspective view of the electronic cigarette case; and,

FIG. 9 is a third perspective view of the electronic cigarette case shown in an open state of use.

The broken lines in the drawings depict environment that forms no part of the claimed design.
